UNITED STATES PATENT OFFICE.

ERNEST C. FOX, OF CLEVELAND, OHIO.

DESIGN FOR A REGISTER-BOX.

SPECIFICATION forming part of Design No. 31,239, dated July 18, 1899.

Application filed May 22, 1899. Serial No. 717,849. Term of patent 7 years.

To all whom it may concern:

Be it known that I, ERNEST C. FOX, a citizen of the United States, residing at Cleveland, county of Cuyahoga, State of Ohio, have 5 invented and produced an original Design for a Register-Box, of which the following is a specification, reference being had to the accompanying drawings, forming part thereof.

Figure 1 is a top view of a box, showing the 10 characteristic features of my design; and Fig. 2 is a bottom view thereof. Both these views are in perspective, showing all parts thereof, interior and exterior.

As shown in the drawings, the leading or material features of the invention consist in the 15 unitary design comprising the rectangular frame 1, which is attached to the register, and the slightly-tapered flange 2, which is curved, as shown, to conform to the shape of the fur-

nace-pipe, the curve of the flange 2 being 20 within the frame 1. The inner extremity of the curved flange 2 is connected with the inner edge of the frame by means of the plane surface 3. The sides of the frame are shown as slightly curved outward at 4 to correspond 25 with the curve of the flange 2.

Having described my invention, what I claim as new, and desire to secure by Letters Patent, is—

The design for a register-box, substantially 30 as shown and described.

Signed by me, at Cleveland, Ohio, this 4th day of May, A. D. 1899.

ERNEST C. FOX.
